FIG. 7.

UNITED STATES PATENT OFFICE.

JAMES STANBURY CREEDY, OF HAMILTON, ONTARIO, CANADA.

JOURNAL-BOX LID.

1,344,175.

Specification of Letters Patent. Patented June 22, 1920.

Application filed December 16, 1918. Serial No. 266,936.

To all whom it may concern:

Be it known that I, JAMES STANBURY CREEDY, of the city of Hamilton, in the county of Wentworth, in the Province of 5 Ontario, Canada, have invented certain new and useful Improvements in Journal-Box Lids, of which the following is the specification.

My invention relates to improvements in 10 journal box lids and the object of the invention is to devise a boltless lid which will dispense with the loose hinge bolt and may be opened and closed with facility and when closed or even when left open will not rattle 15 or make a noise, in which the fit will be close and practically air tight and will not allow of any slopping over of the oil and it consists essentially of the following arrangement and construction of parts as hereinabove 20 after more particularly explained.

Figure 1 is a perspective view of a journal box showing my lid in the closed position.

Fig. 2 is a similar view to Fig. 1 showing the lid in the open position.

Fig. 3 is a longitudinal section through Fig. 1.

Fig. 4 is a longitudinal section through Fig. 2.

Fig. 5 is an enlarged perspective detail of 30 the hinge connection of the lid.

Figs. 6 and 7 are perspective details of the parts forming the hinge connection shown in Fig. 5 separated apart.

In the drawings like characters of reference 35 indicate corresponding parts in the various figures.

1 indicates the body of the journal box, the lower front portion of which is provided with an upwardly inclined portion 1^x to 40 form an oil well at the bottom of the journal box in accordance with the usual practice.

2 indicates a boss which extends upwardly from the top of the journal box and from the upper edge of the mouth 1' of such box. 45

2^x and 2' indicate rectangular studs extending outwardly from each side of the box 2, which studs are deeper than they are wide so as to prevent the lid falling off when it is open as will hereinafter appear. The 50

studs are provided with heads 2² and 2³ which are offset slightly upwardly. 3 indicates a pair of lugs which extend forwardly from the base of the boss 2 and from the upper edge of the mouth 1' of the journal box. 4 indicates my journal box lid 55

which is provided at its hinge point with an outwardly extending hooded portion 4^x, the side walls 4' and 4² of which are formed hollow, the inner wall portions 4³ and 4⁴ of such hollow wall portions 4' and 4² being 60 provided with orifices 4⁵ and 4⁶ from which extend slots 4⁷ and 4⁸, such slots extending between the orifices 4⁵ and 4⁶ and the vertical edges of the wall portions 4³ and 4⁴. The slots 4⁷ and 4⁸ are sufficiently wide to 65 allow of the passage of the studs 2^x and 2' into the orifices 4⁵ and 4⁶, the heads 2² and 2³ entering into the space formed by the hollow wall portion and being sufficiently large to prevent lateral movement of the 70 cover. The end edges 4⁹ and 4¹⁰ of the slots are raised and form a stop against which the deep side of the studs abut when the lid is raised, and prevent the lid being shaken off, see dotted lines Fig. 4 and full 75 lines Fig. 5.

5 and 6 indicate a pair of bosses which depend inwardly from the inner face of the cover and extend longitudinally thereof at each side of the center. The bosses 5 and 6 80 are provided with orifices 5^x and 6^x provided with enlarged inner ends 6' as indicated by dotted lines in Figs. 3 and 4. 7 indicates a U-bolt provided with a lug 7^x extending from the center of the base of the U, such 85 lug extending between the lugs 3 of the journal box. The lugs 3 and lug 7^x are provided with aligned holes through which a pivot 7' extends. The side portions of the bolts 7 forming the U extend freely into 90 the orifices 5 and 6 and are provided near their bases with enlargements 7⁰ between which and the reduced portion of the orifices 5 and 6 extend compression springs 8, such 95 springs surrounding each of the members forming the U-bolt.

The journal box lid 4 is provided with side flanges 4⁰ fitting to each side of the journal box when the lid is in the closed position. The interior face of the cover is 100 also provided with a surrounding face groove 4⁷ into which the edge of the mouth of the journal box fits when the cover is closed.

It will be seen that when the door is in 105 the open position as shown in Fig. 4 that the pressure of the springs 8 serve to force the cover up and longitudinally outward thereby drawing the cover in a direction to carry the edge of each orifice 4⁵ and 4⁶ against the 110

studs 2^x and 2^y and hold the cover in a steady position so that it will not rattle. Similarly when the cover is thrown to the closed position as shown in Fig. 3 the compression of the spring is exerted downwardly and inwardly against the bosses 5 and 6 thereby forcing the cover tight against the edge of the mouth of the journal box so that it will not only be kept steady and free from rattling when in this position but also will form a tight fit which will prevent the leakage of oil should it have a tendency to slop over.

What I claim as my invention is:

15 In a journal box, a stud bearing member extending outwardly from the journal box in proximity to the mouth thereof, studs extending from each side of such stud bearing

member, a lid, a hooded portion on the lid having open ended slots in the side walls thereof into which the studs extend, lugs extending forwardly from the upper edge of the journal box, depending bosses extending from the lid having orifices extending therethrough, a U-bolt member pivoted at one end between the lugs and having the arms thereof extending through the orifices of the depending bosses of the lid, and compression springs surrounding the U-bolt members between the lid bosses and base thereof.

JAMES STANBURY CREEDY.

Witnesses.
